(57) **CLAIM**

The ornamental design for a circuit breaker, as shown and described.

DESCRIPTION

FIG. 1 is a front side perspective view of a circuit breaker according to our new design.

FIG. 2 is a front side view of the circuit breaker shown in FIG. 1.

FIG. 3 is a rear side view of the circuit breaker shown in FIG. 1.

FIG. 4 is a left side view of the circuit breaker shown in FIG. 1.

FIG. 5 is a right side view of the circuit breaker shown in FIG. 1.

FIG. 6 is a top side view of the circuit breaker shown in FIG. 1; and,

FIG. 7 is a bottom side view of the circuit breaker shown in FIG. 1.

The broken lines in the drawings illustrate portions of a circuit breaker that form no part of the claimed design.
